US00D971791S

(12) **United States Design Patent** (10) **Patent No.:** **US D971,791 S**
(45) **Date of Patent:** **** Dec. 6, 2022**

(54) **ELECTRIC MOTORCYCLE**

(71) Applicant: **Cake 0 emission AB**, Stockholm (SE)

(72) Inventors: **Stefan Ytterborn**, Stockholm (SE);
David Gonzales, Stockholm (SE);
Oskar Milke, Stockholm (SE); **Marcus Carlsson**, Stockholm (SE)

(73) Assignee: **CAKE 0 EMISSION AB**, Stockholm (SE)

(**) Term: **15 Years**

(21) Appl. No.: **29/828,369**

(22) Filed: **Feb. 25, 2022**

Related U.S. Application Data

(62) Division of application No. 29/779,899, filed on Apr. 21, 2021, now Pat. No. Des. 948,382, which is a division of application No. 29/711,881, filed on Nov. 4, 2019, now Pat. No. Des. 920,852.
